UNITED STATES PATENT OFFICE.

THOMAS CARNEY AND FRANK L. HEWITT, OF DAYTON, OHIO.

FILING-DRAWER.

SPECIFICATION forming part of Letters Patent No. 760,848, dated May 24, 1904.

Application filed August 3, 1903. Serial No. 167,986. (No model.)

To all whom it may concern:

Be it known that we, THOMAS CARNEY and FRANK L. HEWITT, citizens of the United States, residing at Dayton, in the county of 5 Montgomery and State of Ohio, have invented certain new and useful Improvements in Filing-Drawers; and we do declare the following to be a full, clear, and exact description of the invention, such as will enable others skilled in 10 the art to which it appertains to make and use the same, reference being had to the accompanying drawings, and to the letters of reference marked thereon, which form a part of this specification.

15 This invention relates to improvements in filing-drawers especially adapted for the filing of accounts, but which may with equal facility be utilized for the filing of any papers—such, for example, as letters, invoices, &c.

20 The object of the invention is mainly to provide a filing-drawer for accounts which is free from many of the well-known objections attending the filing-drawers now commonly in use. Principally among these objections may 25 be mentioned the mutilation of the account-sheets in turning them over the arch from one side to the other. This mutilation is due to the arches not properly engaging at the joints. In other words, the joints between the arches 30 proper and the front upright posts are more or less uneven or out of a true vertical alignment, and as a result the holes in the sheets become torn and enlarged each time said sheets are caused to move over the joints in the

35 arches in turning said sheets from one side to the other side of the arches. In the present invention the joint between the arches and the forward upright posts is even or uniform, and the diameters at the joints are substantially the same as at any other point of said arches. As a matter of fact, the diameter of the arches, including their front and rear upright portions, is uniform throughout and no 40 obstructive shoulders occur at the joints to

45 mutilate the sheets in throwing them over the arches. The great difficulty heretofore experienced with the arches of filing-drawers is also due to an improper centering or joining of the two arch members. This is obviated in 50 the present invention by providing centering

means on the engaging ends of the arch members, such as will hereinafter be described. In addition to the construction and operation of the arches the invention also appertains to mechanism for the drop-leaf of the drawer, 55 whereby said drawer is locked in an upright position and may be easily dropped from such position to a horizontal position, all as will hereinafter be more fully described.

Preceding a detail description of our invention reference is made to the accompanying drawings, of which—

Figure 1 is a perspective view of our improved filing-drawer, the same having three arches and parts of the base being broken 65 away. Fig. 2 is a detached perspective view of the slide which operates the rear members of the arches to open and close them. Fig. 3 is a cross-section on the line *xx* of Fig. 1. Fig. 4 is a bottom plan view of the mechanism 70 and its supporting-plate detached from the drawer. Fig. 5 is a detached perspective view of the hinged plate which supports the rearward members of the arches. Fig. 6 is a perspective view of our improved filing- 75 drawer consisting of two arches. Fig. 7 is a plan view of the drop-leaf-locking mechanism, portion of the leaf being broken away. Fig. 8 is a sectional view on line *yy* of Fig. 7; Fig. 9, views in detail, showing the means for 80 centering and joining the ends of the arches.

Throughout a detail description of the invention similar reference-letters indicate corresponding parts.

The invention, as illustrated, may consist of 85 two arches or three arches, as the case may require. In either event the mechanism for opening and closing the arches is the same. For example, it is duplicated in the case of a three-arch filing-drawer, as in Fig. 1, while a 90 two-arch filing-drawer (shown in Fig. 6) has but a single cam mechanism to break the joints of the arches to open or close the same.

We will proceed to describe in detail the invention with particular reference to Fig. 1. 95

A designates the base or bottom of the filing-drawer, upon the rearward portion of which a metallic plate *B* is rigidly secured above suitable recesses in the base *A*. Rising from this plate *B* are the stationary upright members *L* 100

of the arches, said stationary members being provided with centering-points *a*, projecting from their upper ends, which are surrounded by shoulders *b*. The rearward members *L'* of 5 the arches are rigidly secured to a rocking bar *K*, which may be either round or square in cross-section, said bar having its ends terminating in journals *N*, which are mounted in ears *M*, that project upwardly from a plate *C*. 10 The ends of the arches *L'* which engage with the front members *L* of the arches have centering-cavities *c*, which fit over the points *a* of members *L* and properly center both members and form a smooth joint *L''*. The arches, 15 as shown in Fig. 1, are throughout their lengths in cross-section of an oval form, and the cross-sectional diameter of said arches is uniform throughout from end to end. This is so even at the joints *L''*. This is due to the 20 means for properly centering the members of the arches, as shown in Fig. 9. The advantage of this smooth joint will be readily appreciated when it is understood that the sheets may be moved from one side to the other of 25 the arches without being mutilated or torn in the operation.

The plate *C*, hereinbefore referred to, has a suitable number of hinged extensions *D*, by means of which a hinge connection is provided 30 between the front edge of said plate and the base-plate *B*, said hinged connections in the present case being in the form of a continuous rod *D'*.

O designates one or more upturned flanges 35 formed from the body of the plate *C* and provided with uniform cam-slots *O'*.

Q is a transverse oblong slot in the plate *C*, which receives a pin *R*, that projects downwardly from the bar *K*. Below the plate *C* 40 the slide *E* is placed.

It will be understood that in the drawer-base *A* immediately below the base-plate *B* there are suitable recesses provided. One of these recesses is for the longitudinal hinge-rod *D'*, and the other of said recesses provides 45 operating-space for the slide *E*. This slide has a finger-piece *J* at one end, by means of which it is moved longitudinally to open or close the rearward members of the arches 50 through the following mechanical means:

F designates two oblong guide-slots in the ends of the slide *E*, which receive broad-headed guide-screws *F'*, which secure said slide *E* to the under side of the base-plate *B* and whereby 55 the slide *E* is maintained in the proper position in the sliding movements thereof.

P designates one or more upturned ears projecting laterally from the slide *E* and having cam-pins *P'*, which enter the cam-slots *O'* of 60 the plate *C*. *G* is a cam-slot in the central portion of the plate *E*, a portion of which lies below the slot *Q* and receives the lower end of the pin *R*. Through the means of these slots and pins two distinct movements are im- 65 parted to the rear members *L'* of the arches

in opening and closing said arches. When the slide *E* is moved to its extreme inner position by pushing on the finger-piece *J*, the pins *P'* occupy the highest positions in the slots *O'*, and in such positions the arches are 70 locked firmly at the joints *L''*, as in Fig. 1 or Fig. 6. In this position the upper side of the bar *K* is level. In moving the slide outwardly to throw back the rearward members *L'* of the arches, and thus open said arches, the pins 75 *P'* move downwardly into the lowest parts of the slots *O'*. In thus moving into the lowest parts of the slots the hinged supporting-plate *C* is sufficiently elevated upon its hinges to disengage the joints *L''* of the arches, the extent of such elevation being sufficient to elevate the rear members of the arches to an extent that clears the centering-points *a*. Simultaneously with this elevating movement the bar *K* is rocked by the curved portion of 80 the slot *G* in the slide *E* engaging the pin *R*. The effect of this is to throw the rear members *L'* of the arches back, and thus clear the ends of the front members *L*, or, in other words, open the arches. In the rocking movements of the bar *K* the pin *R* is permitted to move, owing to the slot *Q* being in a transverse position in the plate *C*. The only purpose of said slot *Q* is to enable the pin *R* to pass therethrough and to enter the cam-slot *G* 95 in the slide *E*.

The actuating mechanism for locking the drop-leaf *S* will now be described. The said drop-leaf is hinged to the base *A* by means of hinges *T*, and the actuating mechanism is enclosed by a metallic plate *T'* and consists of a bolt *d*, which is normally pressed outward by a coil-spring *e* across a slot *f* in the drop-leaf. *g* is a locking-arm secured to the base *A* in a position for the end *g'* thereof to enter the slot *f*, the said end *g'* having an opening therein which receives the bolt when the hinged leaf is moved to the position as shown in Fig 6. *h* is a cam having a projection *h'*, which lies in a slot *d'* in the bolt *d*. This cam lies in a suitable recess in the hinged leaf and is fixed to a shaft which projects through said leaf and has a finger-knob *i* secured to it on the outer side of said hinged leaf. By turning this finger-knob the locking-bolt may be 110 moved from the opening in the locking-arm *g* and the leaf thereby permitted to drop to a horizontal position.

Having described our invention, we claim—

1. In a filing-drawer, arches, the rearward members of which are mounted upon a rocking bar, a hinged plate upon which said bar is mounted, a slide for elevating said hinged plate and therewith the rocking bar to disconnect the forward and rearward members of the arches, and coacting means on said rocking bar and said slide for opening the rearward members of the arches, substantially as set forth.

2. In a filing-drawer, arches, the rearward

members of which terminate in a horizontal rocking bar, a hinged plate upon which said bar is mounted, a slide below said hinged plate, and cam connections between said slide, 5 hinged plate and rocking bar whereby the rearward members of the arches are opened and closed and are locked in their closed positions, substantially as set forth.

3. In a filing-drawer, the combination of arches, a rocking bar upon which the rearward members of said arches are mounted, a hinged plate below said rocking bar and adapted to elevate and lower the rearward members of the arches, a cam-slide below said hinged plate and 15 connections between the cam-slide, hinged plate, and said bar whereby the hinged plate is elevated and lowered, and the bar which supports the rearward members of the arches is simultaneously oscillated to open or close the 20 arches, substantially as set forth.

4. In a filing-drawer, the combination of arches, a rocking bar with which the rearward members of said arches are connected, a hinged plate to which said rocking bar is attached, 25 said hinged plate having slotted projections, and a slide below said hinged plate, said slide having pins engaging with said slotted projections, and a cam-slot which receives a pin projecting from the rocking bar of the rearward 30 members of the arches, and whereby in the longitudinal movements of said slide, the arches are opened or closed, substantially as set forth.

5. In a filing-drawer, the combination with arches, the rearward members of which terminate in a lower horizontal bar, a hinged 35

plate upon which said bar is mounted, a slotted projection extending from said hinged plate, and a slide movable below said hinged plate, said slide having a pin which engages the slotted projection on the hinged plate and imparts 40 opposite movements to said plate to raise or lower the rearward members of the arches, and said slide having a cam-slot which is adapted to receive a pin projecting from the lower hinged bar of the rearward members of the 45 arches, and whereby said rearward members of the arches are given oscillating movements to open and close said arches simultaneously with the lowering or elevating movements imparted thereto by the slide, substantially as set 50 forth.

6. In a filing-drawer, the combination of arches, the rear members of which are adapted to a slightly-vertical movement in disengaging and engaging the forward members, and 55 oscillating movements in opening and closing said arches, an operating-slide, and means interposed between said operating-slide and the rear members of the arches whereby the longitudinal movements of said slide impart to 60 the rear members of the arches the movements herein specified.

In testimony whereof we affix our signatures in presence of two witnesses.
